Clemir J. Ney, of Lowell, Mass.
Assignor to Lowell Manufacturing Company,
Letters Patent No. 1170, Dated Nov. 22, 1869.

The schedule referred to in these Letters Patent and making part of the same.

To all whom it may concern:

It is known that, Clemir J. Ney, of Lowell, in the County of Middlesex, and State of Massachusetts, have originated and designed a new pattern for Carpets or other fabrics, of which the following is a full, clear and exact description, reference being had to the accompanying drawings, making part of this Specification.

A. at the top of the design, is one half of a rosette bordered by small balls. 1 and 2. are groups of leaves and flowers lying at equal distances from fig. A. and resting on the ground B. said ground is surrounded by lace work 3.

C. at the bottom of the design is half of an irregular figure supporting the block 4. Branch work 5. surrounds fig. C. and extends under the mottled scrolls D.D.E. in the center is a fan shaped figure connecting the scrolls D.D. and overlapping the lace work 3. 6. 6. and 7. 7. in the corners, when matched from a figure similar to E. The rings F. (each of which surrounds a sprig of coral) when the sides are matched, form a continuous chain throughout the design and surrounding the groups 8. 8. at the sides.

The colors employed in the different portions of the design may be varied to suit the taste and wish of the manufacturer

~ Claim ~

What I claim as my invention and desire to secure by letters patent, is the design or pattern for Carpets herein set forth.
